UNITED STATES PATENT OFFICE.

EDWIN F. LARK, OF WASHINGTON, DISTRICT OF COLUMBIA.

BABY-CARRIAGE.

1,357,878.

Specification of Letters Patent.

Patented Nov. 2, 1920.

Application filed September 27, 1919. Serial No. 326,818.

To all whom it may concern:

Be it known that I, EDWIN F. LARK, a citizen of the United States, residing at Washington, District of Columbia, have invented new and useful Improvements in Baby-Carriages, of which the following is a specification.

This invention relates generally to vehicles, and has particular application to 10 baby carriages and the like.

The chief characteristic of the invention resides in the provision of a mechanical contrivance arranged upon the running gear of the carriage and operable to move the 15 carriage alternately in a forward and rearward direction, with a view of sustaining a lull that tends to put the infant to sleep or keep it quiet, without requiring the services of an attendant.

Another important object of the invention resides in the provision of means whereby the body of the carriage is automatically rocked, which in addition to the alternate rolling of the carriage to and fro, 25 provides all that is needed to pacify the infant; the means for rocking the body being operable simultaneously with the means for rolling the carriage or independently thereof.

In carrying out my invention I also provide means for automatically regulating the speed with which the carriage is moved to and fro, thus eliminating the possibility of the infant being subjected to undue vibration of the carriage.

With these and other objects in view, it will appear as the following description is read in connection with the accompanying drawings that the invention resides in the 40 construction, combination and arrangement of parts as claimed.

In the drawings forming part of this specification like numerals of reference indicate similar parts in the several views 45 wherein:—

Figure 1 is a side elevation of a baby carriage equipped with the contrivance forming the subject matter of my invention.

Fig. 2 is a sectional view through a spring 50 motor.

Fig. 3 is a plan view thereof.

Fig. 4 is a plan view of the running gear of the carriage showing the contrivance associated therewith.

Fig. 5 is a view of the clutch partly in 55 section.

Fig. 6 is a sectional view through the governor controlling the speed of the carriage.

Fig. 7 is a detail view showing the connection of the operating rod with the body of the carriage.

While the invention is shown in use with a baby carriage, for which it was primarily designed and intended, I desire to have it 65 understood that it may be used in any other capacity found desirable, and that its general application is contemplated by the claims.

Referring to the drawing in detail, 70 indicates the body of a baby carriage which is supported by the springs 11, upon the running gear 12, in the usual well known manner. For the purpose of imparting an alternate forward and rearward movement to the 75 carriage, I provide the rear axle 13 with a gear wheel 14 which is loosely mounted upon the rear axle and provided with lugs 15 which coöperate with the clutch member 16 fixed upon the rear axle, for the purpose 80 to be hereinafter more fully described. The spring 17 encircles the axle bearing against the wheel 14 and operating to hold the latter effectively in engagement with the clutch member 16 when these parts are associated. 85

Suitably mounted above and below the gear wheel 14 are relatively small gear wheels 18 over which is trained the chain 19, the latter being engaged at one side by the gear wheel 14. Mounted upon the running gear 90 at an appropriate point is a motor indicated generally at A. This motor may be of any suitable construction, but as shown in this specific instance is in the nature of a spring motor including a main crank shaft 20. 95

Pivoted at one side of the motor and at a point between its ends is an arm 21 mounted to oscillate in a vertical plane, one end of the arm provided with an elongated slot 22 for the reception of the crank shaft 20, 100 through the instrumentality of which the oscillating motion referred to is imparted to the arm 21. The opposite end of this arm 21 is suitably connected to the adjacent side of the endless chain 19, and consequently 105 imparts an upward and downward movement to the chain when the arm 21 is in operation. The rod 24 is suitably connected with the gear wheel 14, the rod in turn being associated with a lever 25 pivoted at a point 110 in its length, to engage the running gear 12 of the carriage. The lever 25 is provided

with a handle 26 by means of which the lever can be operated to throw the gear wheel 14 into and out of engagement with the clutch member 16. The handle 26 is provided with a lug 27 adapted to engage with the notches 28 for holding the parts in a given position. By reason of the construction thus far described it is manifest that when the gear wheel 14 is moved into association with the clutch member 16 the gear 14 rotates with the rear axle 13. The motor being in operation, an oscillatory motion is imparted to the arm 21, the chain 19 being moved up and down imparting rotation to the rear axle 13 in reverse directions. Consequently the carriage is moved alternately in a forward and rearward direction for lulling an infant to sleep, thus eliminating the services of an attendant. It is of course understood that the motor is equipped with a suitable brake by means of which the motor can be thrown into and out of operation at the will of the operator. When it is desired to make use of the carriage in the ordinary manner, or in other words to move the carriage continuously, in a forward direction it is only necessary to disengage the gear wheel 14 from the clutch member 16.

For the purpose of preventing the carriage from being moved to and fro beyond a certain speed, and subjecting the infant to undue vibration of the carriage, I provide a governor for controlling the speed of the carriage under the influence of the motor. This governor is clearly illustrated in Fig. 6 and includes flexible arms 30 provided with the weights 31 which move outwardly under the effect of centrifugal force, bringing the end of the governor indicated at 32 into engagement with a brake disk 33 fixed upon the shaft 34. The governor is actuated from the motor A by means of an endless chain 35 which is trained over the sprocket 36 fixed upon the shaft 37 of the motor and also over a sprocket 38 fixed upon a governor shaft 34.

In addition to moving the carriage alternately in a forward and backward direction, the contrivance forming the subject matter of my invention is also designed to impart a rocking motion to the body 10 of the carriage. For this purpose, the running gear is provided with the brackets 39 and 40 respectively which constitute bearings for a crank shaft 41. The crank shaft is rotated by means of an endless chain 42 which is trained over a sprocket 43 fixed upon the crank shaft 41, and also trained over a sprocket 44 fixed upon the shaft 45 of a motor A. An operating rod 46 is vertically disposed to provide a connection between the crank portion of the shaft 41 and the body of the carriage 10. The rod 46 is formed with an eye 47 at one end, which receives the crank terminals of the shaft 41,

while the opposite end of the rod 46 is connected to the adjacent end of a flexible arm 48 which is secured to the underside of the body 10 and spaced therefrom. Interposed between the arm 48 and the body 10 is a coiled spring 49 for cushioning the movements of said parts, as will be readily understood. As hereinabove stated, the body 10 may be rocked through the instrumentality of the rod 46, while the carriage is being moved to and fro, providing all that is necessary to pacify the infant and sustain a lull that will tend to put the infant to sleep. However, should it be desired to move the carriage to and fro without rocking the body 10, this may be accomplished by simply detaching the rod 46 from the crank terminal of the shaft 41. The rod 46 will then remain suspended from its connection with the arm 48. Again, it is possible to impart a rocking motion to the body 10 while the means for moving the carriage to and fro is out of operation. This is accomplished by permitting the rod 46 to remain associated with the crank shaft 41, and continue the motor A in operation.

While I have shown and described what I consider the preferred embodiment of the invention, I desire to have it understood that I do not limit myself to the exact details of construction, and that such changes may be resorted to when desired as fall within the scope of what is claimed.

Having thus described my invention what I claim as new is:—

1. In combination with a carriage including a body, a motor, means for connecting the motor with the running gear for moving the carriage to and fro, and means actuated by the motor for imparting a rocking motion to the body, and said last mentioned means being operable simultaneously with or independently of the said carriage moving means.

2. The combination with a carriage, a motor, a connection between the motor and running gear for automatically moving the carriage to and fro, and a clutch in said connection for rendering the motor inactive for the purpose stated.

3. The combination with a carriage, of a motor, a gear associated with the rear axle of the carriage, a chain trained over said gear, and a connection between the chain and said motor whereby the carriage is automatically moved alternately in a forward and rearward direction.

4. The combination with a carriage, of a motor, a gear loosely mounted upon the rear axle, a clutch for said gear, a chain trained over said gear and a connection between the chain and the motor whereby the carriage is automatically moved to and fro.

5. The combination with a carriage, of a motor including a crank shaft, an arm piv-

oted between its ends, said arm being connected with the crank shaft, and oscillated thereby, a gear associated with the rear axle, a chain trained over said gear, and the adjacent end of said arm being connected with the chain whereby the carriage is alternately moved in a forward and rearward direction.

5 6. The combination with a carriage including a yieldably supported body, of a 10 crank shaft, a motor, a connection between the motor and said crank shaft whereby the latter is rotated, an operating rod connecting the crank shaft with the body whereby rocking movement is imparted to the latter, 15 and a cushioning means interposed between said rod and body for the purpose specified.

7. The combination with a carriage including a yieldably supported body, of a 20 motor, a connection between the motor and running gear for alternately moving the carriage in a forward and rearward direction, a crank shaft rotated by said motor, a 25 rod connecting the crank shaft and body whereby a rocking movement is imparted to the latter, and a connection between the motor and said running gear, whereby said body may be rocked simultaneously with or independently of any movement of the carriage as a unit.

30 8. The combination with a carriage including a yieldably supported body, of a motor, a connection between the motor and

the running gear for moving the carriage to and fro, a crank shaft rotated by said motor, an operating rod for connecting the shaft 35 and body for imparting a rocking motion to the latter, a cushioning means interposed between said rod and body, and said rod being detachably associated with said crank shaft, whereby the carriage may be used for the 40 purpose specified.

9. The combination with a carriage including a yieldably supported body, a motor, a connection between the motor and said body whereby the latter is rocked, and yieldable means arranged beneath said body and forming part of the connection, for cushioning the movements of said parts.

10. The combination with a carriage, of a 50 motor, a gear loosely mounted upon the rear axle, a clutch for said gear, and means actuated by the motor and associated with said gear to automatically move the carriage to and fro.

11. The combination with a carriage, of a 55 motor, a gear loosely mounted upon the rear axle, a clutch for said gear, spaced pinions, a chain trained over said pinions and said gear, and a connection between the chain and motor whereby the carriage is automatically 60 moved to and fro.

In testimony whereof I affix my signature.

EDWIN F. LARK.
